UNITED STATES PATENT OFFICE.

CHARLES S. BURTON, OF OAK PARK, ILLINOIS, ASSIGNOR TO MELVILLE CLARK PIANO COMPANY, OF CHICAGO, ILLINOIS, A CORPORATION OF ILLINOIS.

PHONOGRAPH.

1,264,268.

Specification of Letters Patent. Patented Apr. 30, 1918.

Application filed January 29, 1917. Serial No. 145,037.

To all whom it may concern:

Be it known that I, CHARLES S. BURTON, a citizen of the United States, residing at Oak Park, in the county of Cook and State 5 of Illinois, have invented new and useful Improvements in Phonographs, of which the following is a specification, reference being had to the accompanying drawings, forming a part thereof.

10 The purpose of this invention is to provide an improved construction of a phonograph adapted to be combined with a piano and contained within the casing thereof. It consists in the elements and features of construction shown and described as indicated 15 in the claims.

Figure 1 is a perspective view of a piano embodying this invention.

Fig. 2 is a front elevation of the phonograph mechanism contained in the piano case, showing certain parts of the piano case and mechanism for the purpose of indicating the relative location of the phonograph in the case.

25 Fig. 3 is a vertical section at the line 3—3 on Fig. 2.

The specific purpose of the construction shown in the drawings is to adapt a phonograph mechanism to be mounted in a piano case so as to position the record carrier and the record thereon within the space which is usually available in front of the hammer action, instead of as has heretofore been generally considered necessary, at such position 35 that the record carrier and record stand in the wider space available within the case above the hammer action. For the purpose of so positioning the record carrier and record, the mechanism is designed and constructed to have the record carrier in a substantially erect position, presenting the face of the record to the view of the listener standing in front of the piano.

The general construction of the phonograph mechanism and the means for rotating the record is not herein claimed and is designed to be illustrated and described here only so far as necessary to present the particular features which are modified from the usual construction in order to accomplish the purpose of the present invention.

The drawings show a piano case, 1, containing an automatic player action which is indicated by the tracker box, 2, with a 55 tracker, 3, and with note sheet carrying

rolls, 4 and 5, therein. The roll operating mechanism is indicated by the outline of the frame thereof, shown at 6, at the right hand end of the tracker box. A shaft, 7, extending behind the tracker box is to be understood as connected with the train of the roll operating mechanism. This shaft communicates power for actuating the record carrier of the phonograph mechanism which is carried in the space available in the piano 60 case at the left hand end of the tracker box of the automatic piano playing mechanism, and in front of the hammer action of the piano indicated by the hammer rest rail, 9, and hammers, 10, shown in the customary 65 position with respect to the other parts mentioned of the automatic or player piano. The feature which distinguishes the present invention is the location of the record carrier, 12, of the phonograph in substantially 70 erect position so as to expose the record thereon, facing forward, through the aperture, 14, formed in the front of the piano case for giving access to the phonograph. 75 14^a is a door for closing this opening, conveniently hinged at its lower edge for swinging forward to open, and provided with means for holding it horizontal at open position so that it constitutes a shelf upon which the records may be temporarily lodged 80 when changing the records on the record carrier. This door is rendered ornamental by a symmetrically situated forward swell, 15^a, which serves the mechanical purpose of 85 accommodating the sound box of the phonograph in the cavity which results at the inner side from making the swell at the outer side. For mounting the record carrier in the erect position described and supporting the carrier operating mechanism, a frame, 90 15, is provided mounted upon the foundation board, 1^a, (though this particular method of supporting it is not essential). The power communicating shaft, 7, extending behind the tracker box from the note-sheet-operating motor train situated at the opposite end of the tracker box obtains bearing in this frame, 15, and carries upon its left hand end a disk, 16, which rotates in frictional engagement with a friction pulley, 17, on the shaft, 18, also journaled in said frame, 15, and having the record carrier tablet, 12, mounted upon its forward upper end, said shaft, 18, being journaled in horizontal position in said frame, 15, ex- 100 105 110

tending therein fore-and-aft as clearly seen in Fig. 3. A means for modifying the speed of the rotation of the record carrier is shown, consisting in mounting the pulley, 17, slidably on the shaft, 18, the hub of the pulley being grooved and engaged by a forked arm, 21, having loose pivotal connections with a sleeve, 22, which is mounted upon a threaded shaft, 23, journaled in the frame, 15, and provided with a hand-wheel, 24, by which they may be rotated to cause the threaded sleeve to travel longitudinally upon it and thereby cause the forked arm similarly to slide the friction pulley, 17, along the shaft, 18, to vary the distance from the center of the friction disk, 16, at which said pulley is frictionally engaged.

The tone arm, 30, 31, is jointed at 32, the member, 30, which carries the sound box, 33, being hinged to the member, 31, said latter member being pivoted for swinging in a plane parallel to the record and carrying the sound box across the latter for playing. The said member, 31, is pivoted as described to the fixedly-supported horn bracket, 34, by center-point screws, 35 and 35^a, the former set through the back wall of the horn bracket and engaging the closed end of the discharge arm of the tone arm elbow, 30 and the latter set through the overhanging end of a bracket, 36, secured to said horn bracket, 34. The discharge arm of the elbow is skeletonized for lateral discharge of the vibrations into the horn bracket, 34. Upon considering the relation of the tone arm and sound box to the erect record which results from making the record carrier erect as described, it will be seen that when the tone arm is pivoted to the horn bracket in proper position to cause the sound box stylus to move across the record in a direction substantially radial thereto, as it should for proper reproduction at all points of its path, the center of gravity of the tone arm and sound box, that is, of the structure which is mounted for pivotal movement about the axis of the swivel joint of the elbow to the horn bracket, will tend to assume a position in the vertical fore-and-aft plane through said swivel axis, and therefore at every other position there will be a lateral pressure of the stylus in the groove of the record, due to gravity. Since this lateral pressure will vary at all positions in the swing of the sound box and stylus over the record, it will tend to vary the reproduction of the record at different parts, and will also tend to wear the groove on one side or the other, that is, to wear it unequally on the two sides; and it will also make the stylus liable to jump from the groove and swing to the neutral position. To prevent these results there is provided a counterbalance for the tone arm and sound box consisting in the weighted

arm, 40, pivoted at any convenient position where it can be accommodated and connected by a link, 41, with the tone arm, the pivotal connections of the link to the tone arm and to the counterbalance arm being at 70 equal distances from the pivots about which said counterbalance arm and tone arm respectively swing, so as to give the weight, 42, an angular movement about the fulcrum of said arm, 40, equal to that of the tone 75 arm about its fulcrum in the horn bracket, and in an arc reciprocally situated with respect to the arc through which said sound box, (or to be more exact, the center of gravity of the tone arm and its load, namely 80 the sound box) moves in traversing the record.

In view of the erect position of the record, the sound box stylus will not be adequately held to the record by gravity; and 85 the necessary pressure is provided by a spring, 45, stretched from a point on the tone arm member, 30, which is offset toward the plane of the record from the pivot of said member, 30, 31, said spring extending through said member, 31, to the back or top of the elbow and secured thereto. The point of attachment of the spring to the tone arm member, 30, is selected so that when the sound box is withdrawn from the 95 record a certain distance, the line of tension of the spring passes pivot axis of the arm 30 to the arm, 31, and the spring will then react to withdraw the sound box from the record instead of holding it toward the 10 record, and will sustain it in a convenient position for inserting and removing the stylus and introducing a record behind the tone arm on the record carrier.

To prevent the record from accidentally 10 escaping from the center pin of the record carrier and to cause the record to be lodged against the record carrier with sufficient 11 certainty to insure the frictional engagement between the two by which the record 11 is carried with the record carrier, said center-pin is split and the split ends are spread apart and made elastic so that they may be closed together to admit the record onto the pin, which spreading again elastically 11 prevents the escape of the record.

I claim:

1. A phonograph comprising in combination with a flat rotatively mounted record carrier and means by which it is mounted 12 with its flat record-supporting surface in an edgewise upstanding position, a sound-reproducing device and a tone arm upon 12 which it is carried for swinging over the record upon the tablet, a pivotal support for 12 the tone arm in such swinging movement positioned outside the circumference of the tablet at the upper side of the latter whereby said tone arm is pendant from its pivot and a weighted lever pivoted for swinging 12

through an arc above its fulcrum, and connections between said lever and the tone arm for causing them to swing through substantially equal arcs.

- 5 2. A phonograph comprising in combination with a flat rotatively mounted record carrier, and means by which it is mounted with its flat record-supporting surface in an edgewise upstanding position, a sound-
10 reproducing device and a tone arm upon which it is carried for swinging over the record upon the tablet; a pivotal support for the tone arm in such swinging movement, a lever pivoted for swinging through
15 an arc at the opposite side of the lever fulcrum from that of the sound box with respect to the tone arm fulcrum, and connections between the tone arm and said lever for causing them to swing through equal
20 arcs at said opposite sides of their respective fulcrums.

3. A phonograph comprising in combination with a flat rotatively mounted record carrier, and means by which it is mounted with its flat record-supporting surface in an edgewise upstanding position, a sound-reproducing device and a tone arm upon which it is carried for swinging over the record upon the tablet; a pivotal support for
25 the tone arm in such swinging movement; a lever pivoted for swinging about its fulcrum through an arc oppositely positioned with respect to said fulcrum from the position of the sound box with respect to the tone arm fulcrum, and a link connecting said lever with the tone arm for giving to the two equal angular movement about their respective fulcrums.

4. A phonograph comprising in combination with a flat rotatively mounted record carrier, and means by which it is mounted with its flat record-supporting surface in an edgewise upstanding position, a sound-reproducing device and a tone arm upon
40 which it is carried for swinging over the record upon the tablet; said tone arm being

jointed between the sound box and its said pivotal support for swinging the member which carries the tone arm toward and away from the record, and a spring connected to 50 the sound-box-carrying member of the tone arm at a point offset toward the plane of the record from the hinge pivot of said member to the other member of the tone arm, and reacting from its point of attachment to said member back along the length of the other member of the tone arm, the hinge connection between the two members of the tone arm being adapted to permit the sound-box-carrying member to be swung 55 about said hinge to carry the sound-box away from the record through an angle sufficient to carry the line of tension of said spring past the hinge pivot.

5. A phonograph comprising in combination with a flat rotatively mounted record carrier, and means by which it is mounted with its flat record-supporting surface in an edgewise upstanding position, a sound-reproducing device and a tone arm upon which it is 60 carried for swinging over the record upon a tablet in a substantially vertical plane, the tone arm being jointed between the sound box and its said pivotal support for folding at its said joint to carry the sound 65 box toward and from the record, and a spring connected at a point on the sound-box-carrying member of the tone arm offset from the hinge pivot toward the record and stretched longitudinally of the other member 70 of the tone arm within the latter toward the pivot; whereby the swinging of the sound-box-carrying member to carry the sound-box away from the record carries the point of attachment of said spring to 75 80 said swinging member past the hinge axis, the spring being strong enough to hold the sound box away from the record.

In testimony whereof, I have hereunto set my hand at Chicago, Illinois, this 26th 85 day of January, 1917.

CHARLES S. BURTON.
